Primary Examiner—Nelson C. Holtje**Attorney, Agent, or Firm—Richard C. Litman****[57]****CLAIM**

The ornamental design for a combined clock and table lamp, as shown and described.

DESCRIPTION

FIG. 1 is a front perspective view of a combined clock and table lamp showing my new design;

FIG. 2 is a rear elevational view thereof;

FIG. 3 is a front elevational view thereof;

FIG. 4 is a left side view thereof, the right side view being a mirror image thereof;

FIG. 5 is a top plan view thereof; and,

FIG. 6 is a bottom plan view thereof.

The broken-line cord of FIG. 1 is environmental only and forms no part of the claimed design.

FIG. 1

FIG. 2

FIG. 3

FIG. 4

FIG. 5

FIG. 6
